UNITED STATES PATENT OFFICE.

ALLISON J. THOMPSON, OF CLEVELAND, OHIO.

LAMP HANGER.

Application filed October 31, 1919. Serial No. 334,897.

To all whom it may concern:

Be it known that I, ALLISON J. THOMPSON, a citizen of the United States, residing at Cleveland, in the county of Cuyahoga and State of Ohio, have invented certain new and useful Improvements in Lamp Hangers, of which the following is a specification.

This invention relates to lamp hangers and particularly to that class of such devices which are of the separable type, to wit, the one in which the lower member carrying the lamp is lowered for the purpose of replacement and cleaning of the lamp.

One important feature of the present invention is the improved arrangement of individually yielding and floating contacts and supports therefor carried by the main hanger member and adapted for co-operation with contacts carried by the lower hanger member. Another feature of the invention consists in the improved construction and arrangement of the hanger base which forms a part of the lower hanger member and affords convenient support for the lower contacts and also for the lamp. A further feature of the invention is an improved latching mechanism arranged in a manner such that the members are firmly held in position with respect to each other and lost motion between the parts, when assembled, is avoided.

The invention also relates to other features which will more fully and in detail appear from the following description, drawings and claims.

In the drawings, Fig. 1 is a vertical sectional view of the hanger; Fig. 2 is a bottom plan view of the lamp hanger member; Fig. 3 is a sectional view through the center of the device taken at 90° of the view shown in Fig. 1; Fig. 4 is a section upon the line 4-4, Fig. 3; and Fig. 5 is a section upon the line 5-5, Fig. 3.

In the arrangement shown, 1 represents a suitable support, which in one construction is in the form of a sheave housing provided with a throat portion 2 for the entry of a rope 3, a sheave 4 mounted upon a pin 5 and a suitable flange 6 adapted to be secured to the main hanger member, as will appear. This sheave support may be utilized or any other preferred form of support may be employed, the only object of any support in this instance being to provide a means for supporting the main hanger member.

The main hanger member comprises a canopy or housing 7 having a lower open end

with flared sides, as shown. This canopy or housing is provided, as shown in Fig. 4, with hollow tubular extensions 8 for the incoming wires. Suitable insulators 9 may be arranged in these extensions. One of these insulators is shown in Fig. 1. The canopy is provided with an upper pad 10 for engagement with the flange 6 and is held thereagainst in a manner which will later appear. Engaging the upper surface of the inside of the canopy or housing is a guide tube flange comprising an ear 11 and two opposed ears 12 and 13, these ears being provided with openings for receiving screws 14 which pass through the ears, through the housing, and engage in the flange 6 of the support. These screws serve to assemble the guide tube flange, the housing and the support. Integral with the flange 11 and extending downwardly in substantially the center of the housing is a guide tube 15 having a beveled edge 16 common to this class of apparatus. The side of the guide tube 15 between the ears 12 and 13 is provided with a slot 17 extending the full length and opening out through the upper part of the cam edge 16, as shown. Extending laterally from the tube and on the sides of the slot 17 are a pair of latch brackets 18 each provided with a notch forming a stop edge 19 and an opening for the reception of a latch pin 20. Loosely mounted upon this pin 20 is a latch 21 provided with a latching nose 22 and a stop pin 23 adapted to engage the shoulders 19 and limit the outward movement of the latch. The latch is so constructed and so arranged upon the pin 20 that it tends to swing into the slot 17 when the stop pin 23 is in any position and even in a position in engagement with the shoulders 19 by reason of the greater mass of the latch being to the right of the pivot 20 as is clearly seen from Fig. 1. The guide tube 15 is provided on its inner wall with annular ribs 24 and 25 above and below the latch, as shown, and for a purpose to be described.

The foregoing description relates entirely to the mechanical construction of the main hanger member and the main hanger member contact apparatus will now be described.

On either side of the guide tube there is a complete contact mechanism and the description of one of these will suffice for both. Each contact mechanism comprises a contact housing 26 of substantially the form shown in cross section in Fig. 4, and open

at its bottom except near its ends where it is provided with inwardly extending webs 27 adapted to receive supporting screws 28 which pass up through the contact housing 5 and are secured in the upper part of the canopy or housing. These webs 27 form stops for the contact and are adapted to be engaged by oppositely disposed ears or projections 29 formed on the sides of the insulator contact members 30. Each of these insulator contact members 30 is provided with a centrally disposed opening 31 for a spring 37 and with a reduced opening 32, shown in Fig. 3, adapted to receive the head 10 of a contact screw 33 which passes down through the bottom of the insulator contact member. A shoulder 34 is obviously formed near the bottom of the insulator contact members and this shoulder is adapted to receive 15 an insulator disc 35 and above it a metallic disc 36. Engaging this disc 36 is a spring 37 which thrusts against the underside of the top of the canopy or housing and is centered by a suitable boss 38 provided at 20 this point. The space below the insulator disc 35 and about the head of the contact screw 33 is filled with plastic insulating material. Engaging the contact screw 33 is a contact sleeve 39 threaded onto the screw 25 and adapted to serve as a binder for one of the leads or incoming wire terminal 40, the wire being held between the sleeve and the insulator contact member. Suitable washers 41 and 42 may be provided at this point, 30 if desired. The contact sleeve 39 is provided with a contact head 43 having an internal conical contact surface 44 therein. It will be seen from the foregoing description that the contacts themselves are directly 35 connected to the incoming leads, that they are individually yieldingly mounted and that the contact heads present the same contacting surface irrespective of their position when the leads are fastened in place. 40 It will further be seen that the individual yielding feature of the main hanger member contacts will insure uniform bearing of the contacts irrespective of the position of the other contact members to be described. 45 The lamp hanger member comprises a latch stem and a base and these parts will now be described. Secured to the end of the rope 3 is a latch stem 45 contracted as its upper end, to wit, at 46 and provided with an 50 opening 47 for receiving the rope, a knot formed on the end of the rope serving to provide a securing means. This stem is of a suitable length, and is of a size in outside dimension, so that it may slide freely within 55 the annular ribs 24 and 25. It is provided at its lower end with an enlargement 48 providing a cavity for the knot of the rope 3. This enlargement is externally threaded and has a V-shaped longitudinally 60 extending groove 49 cutting the threads for 65 a purpose which will appear. This latch stem is provided upon one of its sides and at a point opposed to the recess 49 with a laterally extending latch throwing fin 50 having a horizontally disposed shoulder 51 adapted 70 to engage the under part of the latch 21 and move the same in a counter clockwise direction, as shown in Fig. 1. This fin is also provided with a web 52 inclining toward the tube but cut away at a greater angle to form 75 an inclined edge 53. These inclines are directly below a supporting lug 54 which is located near the upper end of the latch stem. This web 52 controls the inward movement 80 of the latch and insures it engaging the latch stem and the supporting lug at their junction. The two inclines at their junction form a projection or shoulder which engages the latch and starts it moving outward before the shoulder 51 reaches the 85 latch. As shown in Fig. 1, the tendency of the latch is to force the latch stem, by somewhat of a toggle action against the ribs 24, 25 when tension upon the rope is relieved. The latch stem when in supporting position 90 extends into a suitable opening 54 in the canopy or housing and this opening communicates with the opening in the support or sheave housing. 95 The hanger base already referred to comprises a hollow hub 55 threaded internally to receive the enlargement 48 and provided with a boss 56, Fig. 1, for receiving a thumb screw 57 adapted to engage in the recess 49 for positioning the hanger base and holding the same in place. 100 The hollow hub converges and terminates at its lower end in a threaded nipple 58 to which the lamp is secured. The hub 55 is further provided with opposed lead canopies 105 59, 60 which protect lead openings 61 and 62 respectively, extending through the hub, as shown in Fig. 1. These openings are for the lamp leads, not shown. 110 Extending laterally from the hub 55 of the hanger base are supporting eyes 63 and 64 each of which supports a lower contact and since these contacts are identical in form a description of one will suffice for both. 115 Each of these lower contacts consists of two similar insulators 65 and 66, each having a reduced portion 67 adapted to fit loosely in the opening of the eye, a suitable layer 68 of yielding insulating material being arranged between the reduced portion 67 of the insulators. Both of the insulators 65 and 66 are provided with centrally disposed openings for the reception of the contact shank 69, each of which is provided at its upper end with a contact cone 70 and at its lower end with threads for receiving a securing nut 71, a washer 72 being interposed between the nut and the insulator. A suitable binding nut 73 and washers 74 are provided on each shank whereby the lamp 120 125 130

leads may be secured to these contacts. The shank 69 is surrounded by an insulating tube 75 arranged in the openings in the insulators for preventing leakage of the current. The 5 insulators 65 and 66 are loosely arranged within their housings whereby they may float within the lamp hanger member and permit self-adjustment of the contacts of this member.

10 The latch stem is provided with stops 76, one on each side for engaging the guide tube and limiting the upward movement of the lamp hanger member.

15 The hanger base is assembled in its entirety, to wit, the lamp is secured to the nipple 58, the leads are led out through the openings 61 and 62 and secured in place to the contacts just described. This part of the mechanism is then secured onto the enlargement 48 and the thumb nut 57 is set in the groove 49, when the hanger base will be positioned properly with respect to the latch stem which will be a position with the opposed contacts of this member in a plane 20 at right angles to the latch throwing fin 50 and the supporting lug 54 and this will bring about proper alignment of the upper and lower contacts. It is obvious that the hanger base and the lamp may be removed 25 from the latch stem and taken to any suitable place for cleaning without removal of the rope or without necessitating the cleaning of the lamp at the point where the entire hanger is located or disturbing any electrical connections.

30 In operation, assuming that the parts are in the position shown in Fig. 1 and that there is no tension upon the rope 3, the operator pulls upon the rope sufficiently to cause the raising of the latch stem with the result that the latch releasing fin is moved upward when the shoulder 51 will engage under the latch and throw it in a counter-clockwise direction, thereby releasing it 35 from the supporting lug 54. A quick release of the rope will then permit the entire lamp hanger member to move downwardly to any desired point. At this time the hanger base may be removed, as already described, and taken to a suitable place for 40 cleaning. When it is restored in place upon the latch stem the operator may then pull upon the rope until the lug 54 passes above the latch. A slow release of the rope will 45 then cause the lamp to be supported in proper position with the contacts in engagement and with the several parts held rigidly against lost motion.

Having described my invention, I claim:

60 1. In a lamp hanger, a main hanger member, a lamp hanger member, guiding mechanism for said members, latching mechanism, fixed contacts carried by the lamp hanger member, individual floating yielding contact structures carried by the main hanger

member and co-operating with the fixed contacts of the lamp hanger member, each of said structures comprising a contact housing, a contact insulator having universal movement therein, means for forcing said insulator yieldingly downwardly, and a contact carried by said insulator. 70

2. In a lamp hanger, a main hanger member, a lamp hanger member, guiding mechanism for said members, latching mechanism, 75 fixed contacts carried by the lamp hanger member, individual floating yielding contact structures carried by the main hanger member and co-operating with the fixed contacts of the lamp hanger member, each of 80 said structures comprising a contact housing, a contact insulator having universal movement therein, means for forcing said insulator yieldingly downwardly, and a contact carried by said insulator, said contact 85 having a conical opening at its lower end.

3. In a lamp hanger, a main hanger member, a lamp hanger member, guiding mechanism for said members, latching mechanism, 90 conical fixed contacts carried by the lamp hanger member, individual floating yielding contact structures carried by the main hanger member and co-operating with the conical fixed contacts of the lamp hanger member, each of said structures comprising 95 a contact housing, a contact insulator having vertical and lateral movement therein, means for forcing said insulator yieldingly downwardly, and a contact carried by said insulator, said contact having a conical opening 100 at its lower end.

4. In a lamp hanger, a main hanger member, a guide tube carried thereby and having a bearing surface, a lamp hanger member, a latch stem therefor having a co-extensive bearing surface, a supporting lug carried by said latch stem opposed to said bearing surface and having its supporting part within the length of the same, and a pivoted latch supported and arranged to force said latch stem uniformly against the bearing surface of the guide tube and approach the horizontal when in full latched position and thereby prevent movement of said latch stem in the 105 guide tube when the parts are assembled. 110

5. In a lamp hanger, a main hanger member, a lamp hanger member, a main hanger member guide tube having an open ended slot in its side, a latch stem on said lamp hanger member, a supporting lug carried thereby and forming a shoulder adjacent to the stem, said lug being adapted to pass into said slot and a latch pivotally supported in 120 said main hanger member and passing through the slot of the guide tube and engaging the latch stem below the supporting lug so as to cause binding engagement of the stem against the tube.

6. In a lamp hanger, a main hanger member, a lamp hanger member, a main hanger 125

member guide tube having an open ended slot in its side, a latch stem, a supporting lug carried thereby and forming a shoulder adjacent to the stem, said lug being adapted to pass into said slot, a latch pivotally supported in the main hanger member and passing through the slot of the guide tube and engaging the latch stem below the supporting lug and within the tube, and a latch throwing fin projecting from the latch stem and adapted to engage the latch near its pivot to throw the same out of engagement with the supporting lug.

7. In a lamp hanger, a main hanger member, a guide tube to be carried thereby, latching mechanism, a lamp hanger member, inter-engaging contacts carried by the main and lamp hanger members, said lamp hanger member comprising a latch stem for co-operation with said tube, and a hanger base removably secured to the latch stem, said base being provided with canopied lead openings and a nipple for attachment of a lamp.

8. In a lamp hanger, a main hanger member, a guide tube carried thereby, a latch stem, latching mechanism pivotally supported in the main hanger member, means for

positioning the latch stem with respect to the latching mechanism, a hanger base receiving and engaging portion carried by the latch stem, a hanger base having an engaging portion adapted for co-operation therewith, contacts carried by said main hanger member and by said hanger base, and means provided on said hanger base and the supporting portion therefor for positioning the contacts of the lamp hanger member with respect to the contacts of the main hanger member.

9. In a lamp hanger, a main hanger member, a lamp hanger member, a main hanger member guide tube having an open ended slot in its side, a latch stem, a supporting lug carried thereby, a latch pivotally supported in the main hanger member and passing into the slot in the guide tube and engaging the latch stem below the supporting lug, a latch throwing fin projecting from the latch stem below said lug, and an inclined web between the latch throwing fin and supporting lug for controlling the inward movement of the latch.

In testimony whereof I affix my signature.

ALLISON J. THOMPSON.
